UNITED STATES PATENT OFFICE.

ROLAND C. HILTON, OF NEW BEDFORD, MASSACHUSETTS, ASSIGNOR OF
ONE-HALF TO JAMES M. WILLIS, JR., OF SAME PLACE.

VALVE FOR INFLATION.

SPECIFICATION forming part of Letters Patent No. 683,855, dated October 1, 1901.

Application filed February 12, 1901. Serial No. 47,004. (No model.)

To all whom it may concern:

Be it known that I, ROLAND C. HILTON, a citizen of the United States, residing at New Bedford, in the county of Bristol and State 5 of Massachusetts, have invented certain new and useful Improvements in Valves for Inflation, of which the following is a specification, reference being had therein to the accompanying drawings.

10 This invention has for its objects the production of simple, reliable, and inexpensive devices to facilitate the inflation of articles, particularly pneumatic tires, and the prevention of the accidental removal of the head of 15 the device, although said head is well adapted to be revolved within a union secured to the body of the device, as shown in the accompanying drawings, in which—

Figure 1 represents, on an enlarged scale, 20 a longitudinal central section of the parts of the device with the central hollow plug lowered to the bottom of its course and away from the bottom of the head of the valve-stem, as it is during the process of inflation. 25 Fig. 2 is also a longitudinal section of the device with the upper end of the valve-seat carrier in elevation to show its square head in loose engagement with the four walls of a quadrangular chamber within the plug and 30 the valve also in elevation to show portions cut away from its sides for the passage of air. Fig. 3 is a transverse section on line α α of Fig. 1. Fig. 4 is a perspective view of the valve removed from the casing.

35 In said drawings the casing or body H is generally secured within a short rubber tube attached to a hollow rubber tire and is generally provided with annular grooves h in its periphery to increase the adhesion of said 40 short tube thereto. Said body H is outwardly cylindrical, and its interior is also cylindrical; but the upper portion of said interior is of greater diameter, having two collars or shelves formed in its walls. Within the upper portion 45 is placed the valve-seat carrier 6, the exterior of which is cylindrical, except its upper end 5, which is quadrangular. Its middle portion is provided with a flange 7 to rest upon the upper end of the casing H, with a 50 soft washer 9 between them to render that joint air-tight.

Upon the top of the flange 7 of the valve-seat carrier 6 is mounted the head A, which has around its lower end a flange a , by which it is connected to the body H by means of a 55 union B, the inner upper collar of which loosely rests upon the flange a , while its screw-tapped lower end is in engagement with the screw-threaded flange H^2 , projecting around the top of the body H. The screw-thread on 60 said flange H^2 is preferably a left-hand thread, while the screw-thread within the head A is a right-hand thread, so that at the time the pump is connected to the head A the rotation of said head (which acts as a swivel for the 65 tube of the pump) will have a tendency to tighten the connection between the union and the body H, the top of the flange 7 bearing against the under side of the flange b , formed in the interior of the union B. 70

Within the rotatory head is placed a hollow plug E, having a right-hand screw-thread on its periphery and a quadrangular chamber within to receive therein the quadrangular upper end 5 of the valve-seat carrier 6. The 75 top end of the plug E terminates in a thin tubular portion e , which is flattened laterally into an elliptical form after the head f^2 of the valve-stem f has been passed through, and engaging under said head lifts it to lock 80 the valve in a closed position. The valve-stem passes loosely through the valve-seat carrier, so as to have an air-passage between it and said carrier, and carries on its lower end the valve F. The lower end of the valve- 85 stem is of slightly-larger diameter and conical to cause it to center itself within the lower end of the valve-seat carrier.

The valve-seat consists of a soft washer i , the inner portion of which is supported by a 90 flange 8, formed on the lower end of the neck of said carrier 6, and its outer portion is supported on a shoulder 10, formed on the inner face of the casing.

The upper end of the valve-stem f has the 95 head f^2 , by which the valve is pulled up against its seat when the head A is rotated toward the right side, which lifts the plug E to the position shown in Fig. 2.

To prevent the valve F from being blown 100 too far within the chamber G during the process of inflation, and thereby prevent the head

f^2 from closing the top of the passage in the tubular portion e , surrounding the stem f , the inner surface of the casing H has a shoulder h^2 to arrest the valve F , and said valve 5 has its sides cut away at F^2 for the passage of air, even if it is temporarily seated upon the shoulder h^2 .

- Having now fully described my invention, I claim—
- 10 1. In a valve for inflation, the combination of a chambered body internally wider in its upper end having shoulders on the inner face of its wall, a tubular valve-seat carrier partly within the upper end of said body and having a quadrangular head, a screw-plug having a quadrangular chamber to receive said head, a valve, and its stem passing through said plug, an internally-screw-tapped head
  - 15

engaging said plug, and a union joining said head to the chambered body substantially as 20 described.

2. The combination of a chambered body internally wider in its upper end, a tubular valve-seat carrier having a quadrangular head, a screw-plug having a quadrangular 25 chamber to receive said plug, an internally-screw-tapped head engaging said plug, a valve and its stem, and a union connecting the chambered body to its head substantially as described.

In testimony whereof I affix my signature in presence of two witnesses.

ROLAND C. HILTON.
